LUCIEN J. BARIBAULT, OF NEW HAVEN, CONNECTICUT

WINDOW SCREEN

Application filed May 14, 1927. Serial No. 191,311.

This invention relates to an improvement in window-screens, and particularly to corner-braces for that class of window-screens having metal frames.

5 The object of this invention is to provide, at a low cost for manufacture, an attractive and durable window-screen constructed with particular reference to superior rigidity.

With this object in view, my invention consists in a corner-brace for window-screens and the like, comprising a body-portion; two diverging arms extending outward at right angles from the said body-portion near the outer edges thereof and each adapted to fit 15 within a hollow screen-rail; and a forwardly-opening right-angle groove formed in the inner corner of the brace and adapted to receive the end of a cloth-retaining moulding in each of its diverging reaches respectively.

20 In the accompanying drawings:

Fig. 1 is a broken view in elevation of one corner of a screen constructed in accordance with my invention;

Fig. 2 is a transverse sectional view on the line 2—2 of Fig. 1;

Fig. 3 is a similar view on the line 3—3 of Fig. 1;

Fig. 4 is a broken longitudinal sectional view on the line 4—4 of Fig. 1; and

30 Fig. 5 is a perspective view of the corner-brace detached.

In the embodiment of my invention herein shown, I employ a corner-brace comprising a body-portion 10 which in exterior form substantially conforms to the shape of a horizontal hollow sheet-metal rail 11 and a corresponding vertical rail 12. The said body-member is reduced in size so as to form two transverse abutment-shoulders 13 and 14 extending at a right angle with respect to each other and two arms 15 and 16 extending outward from the said shoulders and adapted to respectively enter the interior of the sheet-metal rails 11 and 12 aforesaid. Each of the 40 said rails is formed on its inner edge with a channel 17, into which the edges of the screen-cloth 18 are deflected, where they are held in place by so-called "moulding-strips" 19, as clearly shown in Fig. 2. Formed in the said 45 body-member 10 and aligned at its opposite

ends with the channels 17 of the rails 11 and 12, I locate a right angle moulding-socket 20 which receives the adjacent ends of the moulding-strips 19, as clearly shown in Fig. 1.

55 By preference, I secure the rails 11 and 12 to the arms 15 and 16 of the corner-brace by soldering them in place thereon, so that the end of the rail 11 and the abutment-shoulder 13 will be firmly united as will also the ends of the rail 112 and the abutment-shoulder 14. 60 Thus, in addition to the rigidity obtained by causing the arms 15 and 16 to extend into the interior of the rails 11 and 12, their ends are firmly united to the body-portion of the corner-brace. This construction I have found 65 to be much superior, in so far as a screen thus constructed will retain its rigidity, despite considerable abuse. By interposing the body-member 10 between the ends of the rails 11 and 12, as shown, I avoid the necessity of carefully mitering, into close union, the adjacent 70 ends of the rails 11 and 12.

I claim:

A corner-brace for window-screens and the like, comprising a body-portion; two diverging arms extending outward at right angles from the said body-portion near the outer edges thereof and each adapted to fit within a hollow screen-rail; and a forwardly-opening right-angle groove formed in the inner 75 corner of the brace and adapted to receive the end of a cloth-retaining moulding in each of its diverging reaches respectively.

In testimony whereof, I have signed this 80 specification.

LUCIEN J. BARIBAULT.
